CLAIM

We claim the ornamental design for a heater device for mining cryptocurrency, as shown and described.

DESCRIPTION

FIG. 1 is a front view of the heater device for mining cryptocurrency;

FIG. 2 is rear view of the heater device for mining cryptocurrency;

FIG. 3 is a top view of the heater device for mining cryptocurrency;

FIG. 4 is a bottom view of the heater device for mining cryptocurrency;

FIG. 5 is a right side view of the heater device for mining cryptocurrency;

FIG. 6 is a left side view of the heater device for mining cryptocurrency;

FIG. 7 is a front perspective view of the heater device for mining cryptocurrency; and,

FIG. 8 is a rear perspective view of the heater device for mining cryptocurrency.
